(57) **CLAIM**

We claim the ornamental design for a juicer attachment for blender assembly, as shown and described.

DESCRIPTION

FIG. 1 is a front top perspective view illustrating a juicer attachment of a blender assembly of the present disclosure; FIG. 2 is a rear top perspective view of the juicer attachment of FIG. 1;

FIG. 3 is a first side elevational view of the juicer attachment of FIG. 1;

FIG. 4 is a second side elevational view of the juicer attachment of FIG. 1;

FIG. 5 is a front elevational view of the juicer attachment of FIG. 1;

FIG. 6 is a rear elevational view of the juicer attachment of FIG. 1;

FIG. 7 is a top plan view of the juicer attachment of FIG. 1; and,

FIG. 8 is a bottom plan view of the juicer attachment of FIG. 1.

The broken lines depict portions of the article that form no part of the claimed design.
